UNITED STATES PATENT OFFICE.

MIRIAM GROSS, OF MILWAUKEE, WISCONSIN, ASSIGNOR TO MIRIAM GROSS COMPANY, OF MILWAUKEE, WISCONSIN, A CORPORATION OF WISCONSIN.

DESIGN FOR A KNITTED DRESS.

Application filed February 16, 1929. Serial No. 30,103. Term of patent 7 years.

To all whom it may concern:

Be it known that I, MIRIAM Gross, a citizen of the United States, residing at Milwaukee, in the county of Milwaukee and State of Wisconsin, have invented a new, original, and ornamental Design for Knitted Dress, of which the following is a specification, reference being had to the accompanying drawing, forming part thereof.

In the drawing—

Figure 2 is an enlarged detail of one of the figures, which are apparent in the distinctive stitch employed by way of differentiation from the background portion of the knitted dress.

I claim:

The ornamental design for a knitted dress as shown and described.

MIRIAM GROSS.
